[57] CLAIM

The ornamental design for a beverage dispensing unit, as shown and described.

DESCRIPTION

FIG. 1 is an isometric view of a beverage dispensing unit showing my new design;

FIG. 2 is a front elevation view thereof;

FIG. 3 is a top plan view thereof;

FIG. 4 is a side elevation view thereof, the opposite side being a mirror image of that shown;

FIG. 5 is a rear elevation view thereof; and,

FIG. 6 is a bottom plan view thereof.

FIG. 6

FIG. 5

FIG. 3

FIG. 4

FIG. 2

FIG. 1
